E. WRIGHT.
PICKER FOR LOOMS.

No. 69,380.

Patented Oct. 1, 1867.

United States Patent Office.

EDWARD WRIGHT, OF WORCESTER, MASSACHUSETTS.

Letters Patent No. 69,380, dated October 1, 1867; antedated September 16, 1867.

IMPROVEMENT IN PICKERS FOR LOOMS.

The Schedule referred to in these Letters Patent and making part of the same.

KNOW ALL MEN BY THESE PRESENTS:

That I, EDWARD WRIGHT, of the city and county of Worcester, and Commonwealth of Massachusetts, have invented certain new and useful improvements in Looms; and I do hereby declare that the following is a full, clear, and exact description of the same, reference being had to the accompanying drawings, forming a part of this specification, in which—

Figure 1 represents so much of a loom as is necessary to illustrate my invention.

Figure 2 represents a longitudinal central section of a part of the device shown in fig. 1, and

Figure 3 represents a cross-section of a part of the device shown in fig. 1.

My present improvements relate to the devices used to propel or throw the shuttle in power-looms.

In the drawings the part marked A represents the picker-staff, to the top of which is attached the picker B, which is composed of a metal shell or case, C, of peculiar construction, in which is placed some fibrous material D, to receive the point of the shuttle. The part D may be made of pieces of leather, thick paper, or any other suitable material. The metal shell is made with a flange, a, around the opening b, and also with an offset, c, upon one side of the rear part, which fits upon the picker-staff A. E is a metal spring, bent as shown in the drawings, so that while the back or rear band d, of the shell C, fits into the curve e, the ends f f bear against the back of the picker-staff A, and thus the spring E is made to keep the shell C drawn back, and its flange a, acting upon the part D, keeps that constantly pressed against the front of the picker-staff A, so that both the shell C and its filling D are retained in a secure and proper position upon the staff A. In lieu of the metal spring E, the rear band d of the shell C may be made of such shape that a rubber spring can be used to keep the shell C and filling D securely in place, as before described. The part marked F represents the bottom of the shuttle-box, or one end of the lay of the loom, and as there is nothing new claimed in this part of the loom, it is not necessary to describe it further. The part marked G is simply a standard for supporting the part F, to show the relative positions of the latter and the picker-staff A. The picker-staff A is fastened at the bottom to a rocker, H, of peculiar construction. Rocker H is cored out to receive the lower end of picker-staff A, as shown in the drawings, while the rear part g is slotted out to receive the lever I, which has a curved recess to receive the round projection m upon the rocker H. Lever I extends forward and has a front curved recess to fit the round projection n upon the slotted rocker-stand or table J, which is to be attached to the bottom of the lay in the usual manner. A spring, o, is attached at one end to a projection, p, on the bottom of lever I, and at the other to the bottom of the lay of the loom, or a strap may connect the spring on one end to the lever on the other end of the loom, and thus obviate the use of two springs. The picker-staff may be operated or thrown forward in any of the well-known modes.

The operation is as follows: When the picker-staff is thrown forward to propel the shuttle, the extreme forward position which the picker-staff, its rocker, and lever I, occupy, is shown in blue lines in the drawings, while the extreme opposite positions occupied by the same parts when the shuttle is returned to the shuttle-box are shown in red lines. When the picker-staff is drawn forward, the tongue 1 of the rocker H fits into the slot 2 in table J, and thereby retains the rocker and picker-staff from lateral displacement, while lever I, by its peculiar construction and combination with the rear of rocker H, prevents the latter from sliding forward out of its proper position, and spring o prevents it from slipping back. The part marked 3 of rocker H, and the part 4 of lever I, are both so fitted to each other as to work without binding, and also without rattling. It is important to gradually arrest the back motion of the shuttle before the picker-staff of the loom strikes against the back of the shuttle-box, and many devices have been contrived to arrest the force and motion of the picker-staff and shuttle after the latter has properly entered the box. All such devices have, however, been attended, when put to practical tests, with many objections. By my peculiar combination and arrangement of the rocker H with lever I, table J, and spring o, the picker-staff and shuttle are gradually arrested by spring o after the staff has passed the position shown in dark lines fig. 2. Although it may move back to the position shown in red lines before it is stopped, spring o will bring it back to the position shown in dark lines. It will be observed, when rocker H moves back past the position shown in dark lines, that it elevates the rear end of lever I, and in doing which it has to overcome the resistance of spring o, which then becomes a picker-staff and shuttle-arrester. I am thus enabled to gradually arrest the motion of the shuttle, thereby preventing the displacement of the yarn

upon the cap or bobbin in the shuttle, which is so liable to occur when the shuttle is suddenly arrested. In many cases the shuttles are made so that their points stand a little in front of the centre of the slot in which the picker-staff works, and by making an offset, *c*, in the band *d* of shell *C*, the point of the shuttle will strike upon the part *D* in the centre of the hole *b*, and which point moves in a line nearly parallel to the bottom of the shuttle-box as the picker-staff works back and forth. Spring *E* may be fastened to the staff by a screw, *5*, as indicated in the drawings.

Having described my improvements in looms, what I claim as new, and of my invention, and desire to secure by Letters Patent, is—

The combination of the metal shell *C*, filling *D*, and spring *E*, or its equivalent, with the top of the picker-staff *A*, substantially as and for the purposes set forth.

EDWARD WRIGHT.
